UNITED STATES PATENT OFFICE.

HARRY A. HOUSEMAN, OF PHILADELPHIA, PENNSYLVANIA, ASSIGNOR TO STANDARD MACHINE COMPANY, OF PHILADELPHIA, PENNSYLVANIA, A CORPORATION OF PENNSYLVANIA.

CIRCULAR-KNITTING MACHINE.

1,078,681.

Specification of Letters Patent. Patented Nov. 18, 1913.

Original application filed May 17, 1912, Serial No. 697,861. Divided and this application filed February 14, 1913. Serial No. 748,281.

To all whom it may concern:

Be it known that I, HARRY A. HOUSEMAN, a citizen of the United States, residing at Philadelphia, county of Philadelphia, and 5 State of Pennsylvania, have invented a new and useful Improvement in Circular-Knitting Machines, of which the following is a full, clear, and exact description, reference being had to the accompanying drawings, 10 which form a part of this specification.

As is well known, it is customary, in circular knitting machines, to effect the lengthening or shortening of the stitches by changing the relative vertical positions of 15 the knitting cylinder and cam cylinder. Usually the non-rotatable element (which on some machines is the cam cylinder and on others the needle cylinder) is thus raised or lowered. This operation should be effected with the greatest possible nicety and 20 at the same time with the utmost certainty. It is also desirable to maintain the vertically movable cylinder absolutely level at all times and to provide means for adjusting 25 it to such an exact level without interfering with the lifting and depression mechanism.

It is the object of my invention to provide means for effecting the operations and adjustments above mentioned.

30 In the drawings, which represent a preferred embodiment of my invention Figure 1 is a vertical sectional view of the knitting head with my invention applied thereto; Fig. 2 is a plan view of the main features 35 of my invention.

As fully shown and described in Patent No. 903,190 issued to me November 10, 1908, *d* is the non-rotatable needle cylinder and *i* the rotatable cam cylinder located within 40 the needle cylinder. The needle-cylinder, by means hereinafter described, is supported from the spider *c* projecting upward from the bed-plate *b* of the machine. The needle cylinder has slots *e* extending from the inner periphery outward. These slots contain the needles *f*, which are operated from 45 needle levers *g* pivoted on the comb *h*.

Threaded in the spider *c* are screws 110 (which may be three in number as shown) 50 carrying pinions 111 meshing with an internal rack or gear 112 resting on the spider *c*. Supported on the axles of the pinions 111 are parts 113 secured to the needle cylin-

der. By imparting a rotary movement to the gear 112, the screws 110 are rotated, 55 thereby moving the needle cylinder vertically. By this means a very fine and certain adjustment of the vertical position of the needle cylinder is secured. Further, by lifting gear 112 out of engagement with the screws, any one of them can be independently turned a distance of one or more pinion teeth. This is of special advantage 60 in case the needle cylinder should not be absolutely level, as it can be leveled perfectly 65 by independently adjusting one or more of the screws. The gear 112 may be turned automatically by means of any suitable mechanism, as, for example, by the mechanism set forth in my application filed May 70 17, 1912, Serial No. 697,861. This mechanism forming no part of my present invention, I have simply shown that part thereof more immediately connected with the gear 75 112, namely, a bracket 114 secured to the gear, and a rod 115 pivoted to the bracket and slidable in a bearing in a standard on the upper bed plate *b*. When the rod 115 is moved in the direction of its length, the gear 112 will be turned in one direction or 80 the other, thereby lifting or depressing the needle cylinder. The rod 115 may be provided with one or more adjustable pieces 85 117 each carrying a screw 119 whose axis is parallel to the axis of the rod 115 and which may be operated automatically by a suitable lever (not shown) at the proper time as fully set forth in my said application. It will be understood that if the rod is pushed forward by the lever striking the head of 90 the screw, the gear 112 will be turned in the direction to lift the needle cylinder. The extent to which the needle cylinder will lift may be governed by adjusting the piece 117 on the rod 115, or more conveniently and accurately by turning the screw 119. The extent to which the needle cylinder may be depressed is governed by a screw 220 against which an abutment 221, secured to the gear 112, is adapted to strike on the return movement of the gear 112. The screw 95 220 is adjustable in a bracket 222 secured to the spider *c*. A spring pressed detent 223 engages the grooved head of the screw and holds the screw in its adjusted position. 100 The subject matter of this case is fully 105

disclosed in the application filed by me May 17, 1912, Serial No. 697,861, of which this case is a division.

Having now fully described my invention, 5 what I claim and desire to protect by Letters Patent is:

1. In a circular knitting machine, the combination with the needle cylinder and cam cylinder, one of which is non-rotatable, 10 of a support, pinions rotatable on their axes but not bodily rotatable, said pinions having threaded shafts and being interposed between the non-rotatable cylinder and the support, the threaded shafts engaging one 15 of the last named members at points located on different radii of the non-rotatable cylinder, a gear engaging the pinions, and means to actuate the gear thereby turning all the pinions on their axes and effecting 20 a vertical movement of the non-rotatable cylinder.

2. In a circular knitting machine, the combination with the needle cylinder and cam cylinder, of a support, a plurality of 25 pinions having threaded shafts engaging the support, one of said cylinders having projections resting on the axes of the pinions, a gear engaging the pinions, and means to actuate the gear thereby turning all the pinions and effecting a vertical bodily movement 30 of the last named cylinder.

3. In a circular knitting machine, the combination with the needle cylinder and cam cylinder, of a support, a plurality of 35 pinions interposed between the support and one of the cylinders and having threaded shafts engaging one of the last named members, a rotatable gear engaging all the pinions, whereby when the gear is turned the 40 last named cylinder is raised or lowered, and complementary members, one fixed and

the other on the gear, adapted to abut one against the other and limit the downward movement of the vertically movable cylinder, one of said complementary members 45 being adjustable to vary the limit of downward movement of the vertically movable cylinder.

4. In a circular knitting machine, the combination with the needle cylinder and 50 cam cylinder, of a support, a plurality of pinions interposed between the support and one of the cylinders and having threaded shafts engaging one of the last named members, a rotatable gear engaging all the pinions, whereby when the gear is turned the 55 last named cylinder is raised or lowered and a device connected with and adapted to actuate the gear.

5. In a circular knitting machine, the 60 combination with the needle cylinder and cam cylinder, of a plurality of devices, located on different radii of the cylinders, connected with and adapted to be actuated to move vertically one of said cylinders, and 65 means for simultaneously and uniformly operating all of said devices, said devices being each operable, independently of each other and of said operating means, to vertically move the part of the cylinder connected therewith, whereby said adjustable cylinder may be either leveled by the differential adjustment of said devices or raised or lowered bodily by their simultaneous operation. 70

In testimony of which invention, I have hereunto set my hand, at Phila., Pa., on this 11th day of February, 1913.

HARRY A. HOUSEMAN.
